UNITED STATES PATENT OFFICE.

JULIUS SOBOTKA, OF PLAUE, (VOIGTLAND,) GERMANY.

EMBROIDERING-MACHINE.

SPECIFICATION forming part of Letters Patent No. 322,860, dated July 21, 1885.

Application filed December 15, 1884. (No model.) Patented in Canada January 20, 1885, No. 20,927.

To all whom it may concern:

Be it known that I, JULIUS SOBOTKA, a subject of the Emperor of Germany, residing in Plauen, (Voigtland,) Germany, have invented certain new and useful Improvements 5 on an Embroidering-Machine; and I do hereby declare that the following is a full, clear, and exact description of the same.

My invention relates and is only applicable 10 to those embroidering-machines in which the embroidery is produced by a gang of needles and a gang of shuttles, each needle and shuttle operating to produce embroidery-strokes by interlocking threads—this is to say, to that 15 well-known kind of embroidery-machines using needles and shuttles, to which are also applicable, for example, the inventions covered by the United States Patents Nos. 203,142 and 203,143.

20 The first part of my invention consists in the arrangement of the parts of an embroidering-machine of the before-mentioned type, constructed in such a manner that only the needle-bar is moved toward and away from 25 the cloth, while in the embroidering-machines using needles and shuttles, heretofore known, other parts—such as for holding and guiding the needle-threads or the thread-bobbins—participate also in the reciprocative motion of 30 the needle-bar.

The second part of my invention relates to a mechanism for imparting to the needle-bar the reciprocative motion for moving it toward and away from the cloth.

35 The invention consists, thirdly, in a new mechanism for giving the required intermittent friction to the needle-threads when the stitches are produced.

The fourth part of my invention relates to 40 a mechanism for giving tension to the needle-threads or for pulling the stitches tight.

The fifth part of my invention relates to a 45 device for boring holes into the cloth, which holes form in many cases parts of the embroidery.

The sixth part of my invention relates to an arrangement for making embroideries with threads of two, three, or four distinct colors without changing the threads in each needle, 50 as has heretofore been necessary.

The accompanying four sheets of drawings show only those parts of the embroidering-machine to which my improvements are applied. All the other parts of the embroider-

ing-machine, which undergo no change by 55 the application of my improvements—as, for example, the cloth-frame, the pantograph for governing the same, the shuttles, and the mechanism for imparting motion to the latter—are omitted. The embroidering-machine 60 shown in the drawings has two “stories,” but one story being the mere repetition in regard to its construction of the other story, the new mechanisms are only shown completely in the upper story, and omitted nearly entirely in the 65 lower one.

Figure 1 of the drawings is a vertical transverse section of the part of the machine embodying my invention. Fig. 2 is a vertical longitudinal section of the same, and Fig. 3 a 70 horizontal section of the same. Fig. 4 is a front view, being partly in section; Fig. 5, a cross-section; and Fig. 6, the top view, on a larger scale, of a part of the device for giving friction to the needle-threads. Fig. 7 is a 75 front view; and Fig. 8 a transverse section, on a larger scale, of the needle-bar.

Similar letters refer to similar parts throughout the several views.

As already mentioned above, I only move 80 the needle-bar A toward and away from the cloth, but not any of the other parts, which hold and support the needle-threads and act upon the same, as is done at present.

For reciprocating the needle-bar A, the detailed construction of which is given hereinafter, I employ the following mechanism: The needle-bar A is carried by a number of horizontal cylindrical rods, a, at the ends of which are provided, as hereinafter described more 90 particularly, the bearings, in which the needle-bar A may be revolved round its longitudinal axis. The rods a slide longitudinally in the bearings a', secured upon the transverse beam D, forming part of the frame-work of the embroidery-machine. Each of the rods a is embraced by a ring, a'', rigidly secured thereto, to which is pivoted one end of the connecting-rod a''. The other end of connecting-rod a'' is connected with the end of a lever, a', 100 keyed upon the oscillating shaft b, the latter being supported by the bearings d, secured to the transverse beam D.

The oscillatory motion of shaft b is derived from the rotatory motion of the main or driving-shaft E of the embroidery-machine in the following manner: Upon the driving-shaft E is keyed a revolving disk, B, provided on its inner

side with a cam track or groove, b^5 , in which is kept the roller b^6 , Figs. 1 and 2, turning round a pin traversing the extremity of lever b^4 , which latter is pivoted at c to the frame C 5 of the embroidering-machine. The groove b^5 is so shaped that the lever b^4 oscillates in the required manner, and this oscillation of lever b^4 is transferred by means of the connecting-rod b^2 to the lever b' . The lever b^4 is provided 10 with a rectangular hole, in which slides lengthwise the square block b^7 . The connecting-rod b^2 is pivoted to the block b^7 by means of the pin b^8 , secured to block b^7 , and may, therefore, in consequence of the oscillatory motion of 15 lever b^4 , freely move up and down.

It will now be understood that the oscillatory motion of the shaft b causes a reciprocative motion of the rods a and the needle-bar A, and that the cam-groove b^5 of the disk B must 20 be so shaped as to cause the needles to move toward and away from the cloth as required for the formation of the stitches.

For affording facility to give the needle-threads z the required intermittent tension, I 25 have devised the following mechanism, acting as drag or brake upon the threads: The horizontal angle-iron G, Figs. 4 and 5, is secured to the lugs g^5 of the bearings a' . Upon the angle-iron G are fastened several—in the present instance three—iron bars, g , Fig. 5, of rectangular cross-section, and two other bars, g' , of the same kind, which slide and reciprocate in the intervals of the three bars g , the latter forming the guides for the reciprocating bars 30 g' . Upon all the bars g and g' are secured, by means of the screws g^3 , small wooden blocks g^2 , one end of which is flat and covered with the piece of fabric g , while to the other semicircular end x , Figs. 4 and 6, a piece of emery-cloth is glued. The blocks g^2 are distributed 35 in equal intervals upon the bars g and g' , but the round and rough ends x of the block g^2 upon the bars g are directed opposite to those of the blocks g^2 upon the bars g' , so that 40 each thread z may receive from both sides the friction, Fig. 6. When the formation of the stitches requires that the threads z pass free between the blocks g^2 , the latter have such position that the corresponding blocks g^2 on all 45 the bars g and g' "cover" one another transversely, and that straight transversal intervals are formed between the blocks. As soon as it is, in the formation of the stitches, necessary 50 to break the thread z , the blocks g^2 of the sliding bars g' take such relative position to the blocks g^2 of the fast bars g that the round and 55 rough surfaces x of the blocks g^2 are pressed against the threads z from both sides and give the threads, which are hereby zigzagged laterally, the required friction, Fig. 6.

The reciprocal motion of the bars g' is produced by the following mechanism: Upon the driving-shaft E of the embroidering-machine is keyed an undulated disk, F, against 60 the side of which bears the friction-roller f' , at the end of the lever f , Fig. 2. The other end of lever f , pivoted at f^2 to the frame-work

of the machine, is connected with the extremities of the bars g' , so that the latter are moved to and fro, according to the waves upon the side of disk F. 70

In order that the wooden friction-blocks g^2 may be easily adjusted upon the bars g and g' , each block g^2 is provided with a long hole, g^4 , through which passes the screw g^3 . Before 75 the latter is tightened the block g^2 must be placed in its proper position.

As will be recognized by inspection of the Figs. 1, 5, and 6, to the two outer fast bars g are screwed strips of sheet metal q , provided 80 at the upper edge with rectangular notches, through which the threads z are passed.

I employ, as heretofore, a wire, h' , under which the threads z are led, which wire h' , being secured to the outer ends of the oscillating arms H, pulls back intermittently, the needle-threads z and gives them the required tension; but I employ the following new mechanism for imparting the oscillatory motion to the arms H and to the horizontal shaft h upon 90 which these arms H are keyed: The shaft h oscillates in bearings h^2 attached to the bearings a' .

Upon the driving-shaft E is keyed a cam, J, upon the periphery of which rests the friction-roller i^2 , attached to the end of the lever i^3 , pivoted at i^4 to the frame C of the machine. As the lever i^3 is connected by means of the connecting-rod i^1 with the lever i , keyed upon the shaft h , the oscillatory motion of the lever i^3 will be communicated to the shaft h . 95

The needle-bar A is constructed in the following entirely new manner, which will clearly be recognized by inspection of the detailed views of Figs. 7 and 8: The cross-section of 105 the needle-bar a is nearly rectangular, and resembles that of the cutter-heads of wood-planing machines, Fig. 8, so that several longitudinal edges (four in the present instance) are formed, to which the needles l may be attached by means of the usual needle-holders, k . In this way two, three, or four rows of needles l may be secured to the needle-bar A. In the present instance only three rows of 110 needles are secured to the needle-bar A, Fig. 8, and to the fourth edge of the bar A are secured small brackets K, into which are screwed the boring points or pins L of the kind well known from the "Heilmann Embroidering-Machine." Each row of needles l has threads, 115 which may be of different colors, and each of these rows may, by turning the needle-bar A, be directed horizontally toward the cloth in unlimited alternation, as the pattern of the embroidery may require. 120

The needle-bar A, resting with its cylindrical parts n in the bearings formed by the heads of the reciprocating rods a , Figs. 7 and 8, may be turned freely round its longitudinal axis, and can be maintained securely in one of the 130 positions which correspond to the working position of one of the needle-rows or of the row of boring-points L by means of the following mechanism: Upon the end of the nee-

dle-bar A is keyed a disk, o, provided with horizontal holes o', Fig. 7. A cylindrical pin, m', which passes through a hole formed in the lug m of one of the bearings of the needle-bar A, will, by the action of a flat spring, m³, pressing against the collar m² of pin m', enter with its outer part one or the other of the holes o'. Before the needle-bar A is turned the pin m' must be pulled back and out of the disk o, and when the required row of needles or the row of boring-points is directed toward the cloth S, Fig. 1, in the working position, the pin m' will enter, under the action of spring m³, a hole o' corresponding to the row of needles or boring-points set in working position, so that the latter will be firmly maintained in the desired position. Upon the board N, rigidly secured to the frame of the machine, are placed the thread-bobbins M, which must, in the present instance, have of course thread of three distinct colors.

The needles l of the different rows, and also the boring-points L of the needle-bar A, are arranged in transverse planes of A, so that the guiding-holes of the eye-bar Q, Fig. 1, placed in the usual manner behind the cloth S, may serve for the needles of the different rows.

All the threads z of the bobbins M are led under the oscillating wire h' and over the stationary wire h; but only the threads of the needle-row which is working at the moment are placed between the rough ends x of the braking-blocks g², Figs. 4 and 6. The remaining threads, which are not employed at the moment, are laid in the wire-holders r, secured to the block g² of one of the fast rails g, Fig. 5. When a new row of needles is directed toward the cloth S, the threads of the needle-row before employed are not cut off over the cloth, but remain, even after the respective needle-row is turned away from the cloth, in connection with the same ready for a future operation. The threads of the new needle-row are then, as already mentioned, put between the blocks g², while the threads of the before-employed needle-row are taken out of the intervals of the blocks g² and put in the holders r, Fig. 4.

The boring-points L, which in the present instance are arranged, as above stated, at one of the four edges of the needle-bar A, but in other cases may also be entirely omitted, are used for boring, under the reciprocative motion of the needle-bar A, holes into the cloth S, and which (such bored holes) form in many cases parts of the pattern of the embroidery.

Before the boring-points L, directed toward the cloth S, begin their work the bar p must be turned behind the cloth S and before the eye-bar Q. This bar p is supported by the arms P, pivoted to the shuttle-carriage R, and is provided with holes corresponding with the boring-points L, so that said points L can enter these holes during the forward motion of the needle-bar A when piercing the cloth.

In order that this may be effected it is necessary, as will clearly be seen by inspection of Fig. 1, to move the shuttle-carriage R a little 70 away from the cloth S.

I claim as my invention—

1. The combination of the disk B, keyed upon the driving-shaft E, and provided on the inner side with a cam-groove, b⁵, with 75 lever b⁴, pivoted at c, and provided at the outer end with the roller b⁶, resting in groove b⁵, connecting-rod b², block b⁷, sliding in a rectangular hole of lever b⁴, and connected with connecting-rod b⁸ by means of pin b⁹, 80 lever b', keyed upon shaft b, lever a⁴, connecting-rod a³, ring a², the cylindrical rods a, carrying the needle-bar A, and the bearings a', as described, for moving the needle-bar A toward and away from the cloth, as specified. 85

2. In an embroidery-machine using needles and shuttles, the combination of reciprocating rods a with needle-bar A, journaled to said rods, and carrying outwardly - projecting needles l, arranged in rows, with the stationary bobbins M, arranged in sets with the respective rows of needles on the needle-bar, and with the stationary bar h³ and movable tension-bar h', substantially as specified. 90

3. The combination of the reciprocating 95 bars g', sliding between the fast bars g, attached to the angle-iron G, with the wooden blocks g²; secured upon the bars g and g', one end of the said blocks g² being flat and covered with a piece of fabric, y, while the other end of the blocks g² is circular and covered with a piece of emery-cloth, x, or of other rough material, and with means for reciprocating the bars g', substantially as specified. 100 105

4. The combination of the undulated disk F, keyed upon the driving-shaft E, with lever f pivoted at f', and resting with its roller f' against the side of the disk F, and the bars g', provided with blocks g², having a rounded 110 end covered with emery-cloth, x, or its equivalent, and placed with their rounded ends alternately with the rounded ends of similar blocks attached to the stationary bars g, substantially as and for the purpose specified. 115

5. The needle-bar A, capable of turning on its longitudinal axis, and provided with two, three, or more rows of needles, l, as described, in combination with rods a, connecting-rod a³, lever a⁴, shaft b, and means of oscillating 120 said shaft b, arranged to operate in the manner and for the purpose described.

6. The combination of the needle-bar A with a disk, o, provided with holes o', with the pin m', sliding in a hole of lug m, formed at the bearing of needle-bar A, and the flat spring m³, as described and for the purpose specified. 125

In witness whereof I have hereunto signed my name in the presence of two subscribing 130 witnesses.

Witnesses: JULIUS SOBOTKA.

JOHAN CONRAD DIETRICH,

PAUL HERRMANN DIETRICH.
